DESIGN FOR A TOY GUN

Kenneth A. Duncan, Terre Haute, Ind.

Application July 12, 1943, Serial No. 110,660

Term of patent 3½ years

To all whom it may concern:

Be it known that I, Kenneth A. Duncan, a citizen of the United States, residing at Terre Haute, in the county of Vigo and State of Indiana, have invented a new, original, and ornamental Design for a Toy Gun, of which the following is a specification, reference being had to the accompanying drawing, forming part thereof.

In the drawing:

Fig. 1 is a side elevational view of a toy gun showing my new design;

Fig. 2 is a top plan view thereof;

Fig. 3 is a side elevational view thereof, looking at the opposite side from that depicted in Fig. 1; and

Fig. 4 is an end elevational view thereof.

I claim:

The ornamental design for a toy gun, as shown.

KENNETH A. DUNCAN.
